FIG. 2. shows a perspective view of a stackable shelving unit. The unit consists of a base 15 and a stack of shelves 90. Each shelf 90 has a front panel 30 and a back panel 20. The shelves are interconnected by a central vertical support 13 and horizontal cross supports 14. A handle 12 is attached to the side of the unit.

FIG. 5. shows a perspective view of a shelving unit component. It features a base 90, a front panel 92, and a back panel 93. A handle 94 is attached to the side. A side panel 95 is shown separately.

The shelving unit is shown in three different configurations:

- Top configuration: Shows a single shelf 90 with a handle 12.
- Middle configuration: Shows two shelves 90 stacked together. The top shelf has handle 12 and the bottom shelf has handle 13.
- Bottom configuration: Shows three shelves 90 stacked together. The top shelf has handle 12, the middle shelf has handle 13, and the bottom shelf has handle 14.

Dimensions and labels:

- FIG. 2. dimensions: 1/2, 2.8, 34, 30, 32, 26, 20, 21, 22, 13, 14, 15.
- FIG. 5. dimensions: 90, 92, 93, 94, 95, 96, 91, 50, 50a, 43a, 42, 41, 39, 40a, 47, 44, 48, 53, 53a, 49, 55, 45, 46, 53', 53'', 50a-.

UNITED STATES PATENT OFFICE

2,637,611

DEVICE FOR DISPENSING SANDWICHES
AND THE LIKE

William S. Tandler and David S. Walker, New York, N. Y., assignors to Vendomatic Machine Corporation, New York, N. Y., a corporation of Delaware

Application June 2, 1951, Serial No. 229,608

2 Claims. (Cl. 312—71)

1

This invention relates to improvements in vending and dispensing devices and it relates more particularly to systems for sequentially or cyclically actuating a dispensing device so that rows of articles supported in the device can be discharged one by one from several supports in the device in a predetermined sequence.

As disclosed in the Tandler et al. Patent No. 2,531,238, dated November 21, 1950, a system has been provided heretofore wherein rows of articles supported on trays can be discharged one by one until one of the trays is emptied and thereafter the articles from another tray can be discharged one by one, the discharging means being actuated in a predetermined sequence to empty the trays one after another.

The present invention constitutes a simplification and improvement of the system disclosed in the aforesaid patent whereby the same type of sequential operation can be obtained with many fewer parts and at considerably less cost.

In accordance with the present invention, a typical dispensing device may include a series of supports mounted in a housing, each of the supports being adapted to receive a plurality of articles to be dispensed. The articles are advanced along the supports by means of bead chains which are carried by pulleys at opposite ends of the supports. The pulleys at one end of the support may be carried by a main drive shaft and clutch elements are interposed between the shaft and the pulleys so that the pulleys may be selectively coupled to the drive shaft to be rotated thereby.

To enable the supports to be emptied in succession, we have provided a trigger-controlled mechanism by means of which the unloading or emptying of one of the trays will release a clutch actuating mechanism of an adjacent or different support to thereby couple the pulley of the adjacent or other support to the drive shaft so that the articles thereon may also be discharged one by one until that support is emptied. Each of the supports is provided with a similar trigger mechanism so that the supports will be emptied in sequence until all are emptied.

The trigger mechanism is constructed and arranged so that the power required for operating it is supplied by suitable biasing means so that little effort is required to trigger it and cause the clutch elements to engage. As a consequence, wear and deterioration of the mechanism are reduced to a minimum and little servicing of the dispensing device and long life are assured.

For a better understanding of the present in-

2

vention, reference may be had to the accompanying drawing in which:

Fig. 1 is a view in vertical section through a typical dispensing device embodying the present invention;

Fig. 2 is a top plan view of the dispensing unit of a dispensing device;

Fig. 3 is a plan view of the clutch control and trigger mechanism with the supports for the articles shown in dotted lines to illustrate their relation to the clutch actuating mechanism;

Fig. 4 is a view in section taken on line 4—4 of Fig. 3; and

Fig. 5 is a perspective view of one of the pusher members used for advancing articles along the supports.

The form of the invention chosen for purposes of illustration is a simplified mechanism in which only four supporting elements for articles to be dispensed are disclosed.

Referring now to Fig. 1, the dispensing device may include a casing 10 formed of any suitable material and having a glass front panel 11 through which the interior of the casing may be viewed. Mounted within the casing are a plurality of article supports 12, 13, 14 and 15 which are mounted on cross bars or braces 16 and 17 extending across the housing 10. The articles carried by the supports 12 to 15 are discharged through a suitable chute 18 to a receiving chamber 19 from which the articles may be removed by the purchaser or to a cooking device or the like, as may be required.

As shown in Fig. 2, the supports 12, 13, 14 and 15 are essentially alike so that only one of them will be described herein. The support 12 consists of a channel shaped member 20 having upstanding side flanges 21 and 22 along its longitudinal edges. Both ends of the member 20 are open. At the rear end of the members 12 to 15 is a transversely extending shaft 23 which extends through the flanges 21 and 22 and serves as a support for a pair of idler sprockets 24 and 25 over which are passed the bead chains 26 and 27.

The idler sprockets 24 and 25 are mounted respectively on stub shafts 28 and 29 which extend inwardly from the spaced apart plates 30 and 31 carried by the shaft 23. The sprockets 24 and 25 and their supports extend into notches 32 and 33 in the rear end of the channel member 20 and are normally biased away from the channel member by means of coil springs 34 and 35 wound around the shaft 23 to exert a tension on the bead chains 26 and 27.

The front ends of the chains are received in

notched grooves 38 and 39 in a spool-like pulley 40 which is rotatably mounted on and axially movable with respect to a main drive shaft 41 which extends transversely of the supports 12 to 15 adjacent their front ends. The shaft 41 is driven in a direction to advance the upper flights of the chains toward the pulley 40 by means of the motor 42 which is connected to one end of the shaft 41.

The motor 42 may be started in response to the insertion of a coin in the dispensing device and the actuation of a selector button and stopped by discharge of an article from the support as described in the Tandler et al. Patent No. 2,531,238.

The right hand end of the spool member 40 is provided with clutch teeth 40a which may be engaged with or disengaged from the clutch teeth 43a on a clutch collar 43 which is fixed to the shaft 41. Thus, when the spool pulley 40 is moved to the right to engage the clutch collar 43, the spool pulley is coupled to the shaft 41 and will rotate with it. When the spool pulley 40 is shifted to the left, it is disengaged from the shaft 41 and remains stationary. Each of the supports 13, 14 and 15 is provided with a corresponding spool pulley 44, 45 and 46 and corresponding clutch elements 47, 48 and 49.

The several clutch elements are arranged to be actuated in succession to couple the spools 40, 44, 45 and 46 in succession to the shaft 41. The mechanism for accomplishing this action is shown in Figs. 3 and 4 of the drawing. This mechanism consists of a plurality of triggering mechanisms corresponding to the supports 12 to 15. The triggering mechanisms are mounted on a plate 50 secured to the underside of and connecting the several supports 12 to 15 to produce a unitary construction. The shaft 41 is rotatably mounted in end flanges 50a and 50b on the plate 50. The plate 50 has upwardly and outwardly bent flanges 51 and 52 which extend along its length and abut against the undersurfaces of the supports 12 to 15.

The mechanism for controlling the clutch elements 40 and 43 for the support 12 includes a lever 53 supported at its inner end on a pivot pin 54 extending upwardly from the plate 50. The lever has a forwardly extending end portion provided with a generally vertically extending flange 55 which engages in a groove 56 in the spool pulley 40 adjacent its left-hand end. Thus, clockwise movement of the lever 53 about its pivot 54 will disengage the spool 40 from the clutch collar 43 and counterclockwise movement of the lever 53 will cause the spool 40 to engage the clutch collar 43. The lever 53 is normally biased in a counterclockwise direction by means of a coil tension spring 56 having one end connected to the lever 53 and the other end connected to an anchor pin 57 extending upwardly from the plate 50.

The lever 53 can be retained in a position such that the spool 40 is disengaged from the clutching collar 43 by means of a latch or trigger member 58 consisting of a flat bar or strip of metal 59 mounted for pivoting movement in a horizontal plane about a pivot pin 60 secured to the plate 50. The pivot pin 60 engages the member 59 at about its middle. The right-hand end of the lever or bar member 59 has a notch 61 therein which forms a hook 62 on the end of the lever that engages an offset portion 63 on the lever 53. When the offset portion 63 is engaged with the inner edge of the hook member, the spool

40 is held out of engagement with the clutch collar 43. When the trigger member 59 is rocked counterclockwise, it releases the lever 53 for movement to clutching position to couple the spool 40 to the shaft 41. The member 59 is normally biased in a clockwise direction by means of a tension spring 64 connected to the bar 59 to the left of the pivot 60 and to an anchor pin 65 fixed to the plate 50. The left-hand end or trigger-portion of the member 59 has an outwardly and upwardly directed extension 66 thereon which underlies a generally T-shaped opening 67 near the front edge of the support 13 for a purpose to be described.

The support 13 has a similar clutch actuating and latching member 53' associated with it and also has a trigger member 58' having a trigger extension 66' on its left-hand end which is disposed below a T-shaped aperture 67' in the support 14 and a hook portion 62' at its right-hand end.

The support 14 has another latching and clutch actuating mechanism of the same kind provided with a trigger bar, the left-hand end or trigger-portion 66'' of which underlies a T-shaped opening 67'' in the support 15.

The clutch actuating and trigger mechanism corresponding to the support 15 includes a spring-biased clutch actuating lever 74 like the lever 53 described above, which is engageable by the hook 75 on the right-hand arm of a bell crank 76 which corresponds generally to the trigger bar 59. The bell crank 76 is supported at its midportion by means of a pivot pin 77 extending upwardly from the plate 50. The rearwardly extending arm 78 of the bell crank 76 is connected by means of a transverse link 79 to rearwardly extending arm 80 of another bell crank 81 which is disposed below the support 12. The bell crank 81 is supported by a pivot pin 82 extending upwardly from the plate and has an arm 83 extending to the left so that the extension 84 thereon underlies a T-shaped aperture 85 in the support 12. The bell cranks 76 and 81 are normally biased in a clockwise direction by means of the spring 86 connected to the arm 83 and the pin 57. It will be apparent that if the bell crank 81 is rocked counterclockwise from the position shown, it will cause the counterclockwise movement of the bell crank 76 and disengagement of the hook 75 from the clutch actuating lever 74 to allow the spool 46 to be coupled to the shaft 41 through the medium of the clutch collar 49. Assuming that only the spool 40 is coupled to the shaft 41 as shown in Figs. 2 and 3, only the bead chains 26 and 27 on the support 12 will be moved. The bead chains of each of the supports 12 to 15 are used to advance a pusher member 90 shown in Fig. 5 which has a base plate 91 adapted to extend substantially parallel with the support 12 to 15, a rearwardly inclined, upwardly extending, front flange 92 adapted to engage the rearmost article on the support and a downwardly extending front flange 93 which engages between the beads on the chains

50 and thereby releasably couples the pusher member to the chains so that the pusher member advances with the chains. The pusher member 90 also has narrow end flanges 94 and 95 which are disposed outwardly of the chains and aid in guiding the pusher member. It also has an inverted T-shaped lug 96 extending downwardly from about the middle of the back edge of the base plate 91. The length or height of the lug 96 is substantially greater than the height of the flanges 93, 94 and 95 so that the base plate 91 is

55 60 65 70 75 80 85 90 95 100

tilted forwardly by engagement of the T-shaped lug 96 with the bottom of the support.

As the pusher member 90 is advanced along the support 12, for example, the articles are discharged one by one until the last article on the support is discharged. At about this time, the lug 96 drops into the T-shaped opening 85 in the support 12 and as the pusher 90 continues to advance it will strike the trigger extension 84 on the end of the bell crank 81 and rock it in a counterclockwise direction, thereby rocking the bell crank 76 and releasing the clutch shifting lever 74 corresponding to the support 15 and shifting the spool 46 into engagement with the clutch collar 49 thereby coupling the spool 46 to the shaft 41. The pusher member 90 on the support 12 will continue to move forward until the flange 93 is disposed in front of the spool 40. This disengages the pusher 90 from the chains so that only a light frictional drag is exerted by the pusher on the chains 26 and 27 of the support 12. The T-shaped lug 96 prevents complete dislodgment of the pusher 90 from the support 12 because the T-head engages the support 12 below the narrow part of the opening 85.

The same action takes place successively to the right with the pusher 90 on the support 15 triggering the trigger extension 66' to connect the spool 45 to the shaft, and the pusher 90 on the support 14 striking the trigger extension 66' to connect the spool 44 to the shaft 41 and so on. If after all of the supports have been emptied, the latching mechanism has not been reset, the mechanism will continue to idle with none of the pushers actually coupled to the shaft 41.

Inasmuch as the supports are visible from the exterior of the housing 10, it will be quite evident when the dispensing apparatus is empty. Under ordinary circumstances no "empty" signal or warning signal need be used to indicate an empty condition of the device but, if desired, such an empty signal may be included.

Inasmuch as the apparatus is susceptible to considerable modification in its details and arrangement, the above-described embodiment of the invention should be considered as illustrative and not as limiting the scope of the following claims.

We claim:

1. A dispensing device comprising a plurality of supports for articles to be dispensed, a power driven shaft, a pulley corresponding to each support rotatably and axially movable relative to and mounted on said shaft, a clutch element on each pulley, a cooperating clutch element corresponding to each pulley fixed to said shaft, a lever pivotally mounted adjacent one end and engaging a pulley at its opposite end to move said pulley axially of said shaft, means biasing

said lever in a direction to urge the cooperating clutch elements on said pulley and shaft into engagement, a pivoted latch member adjacent to each lever and having a hook portion engageable with said lever to retain the latter in a position holding the clutch element on its corresponding pulley out of engagement with its cooperating clutch element, an article-advancing member movably mounted on and corresponding to each support, means connecting each article-advancing member to the pulley corresponding to the support on which the article-advancing member is mounted to advance the latter lengthwise of said support upon rotation of the pulley by said shaft, and a trigger arm connected to the latch corresponding to one of said supports in the path of movement of an article-advancing member on another support and movable thereby as the article advancing member approaches said one end of said another support, to release the latch corresponding to said one of said supports and connect its corresponding pulley to said shaft.

2. A dispensing device comprising a plurality of supports for articles to be dispensed, said supports being positioned side-by-side in a substantially horizontal row, a power driven shaft extending transversely of said supports adjacent to one end of said supports, a pulley corresponding to each support mounted rotatably on said shaft, clutch means for connecting each pulley selectively to and disconnecting it from said shaft, bead chains supported on and driven by said pulleys and extending lengthwise of said supports, each chain having one flight resting on top of a support, pusher members resting on each support and having means releasably engaging the said one flight of each chain to cause the pushers to move lengthwise of their supports in response to movement of the chains by said pulleys, a finger extending downwardly from each pusher member, an opening in each support adjacent to said one end thereof into which said finger drops as the pusher approaches said one end, and means below said support and adjacent to said opening and engageable by said finger to actuate the clutch means of a pulley corresponding to another support and connect the last-mentioned pulley to said shaft.

WILLIAM S. TANDLER.
